UNITED STATES PATENT OFFICE

JOHN TOGGENBURGER, OF NEW MILFORD, NEW JERSEY, ASSIGNOR TO UNDERWOOD
ELLIOTT FISHER COMPANY, OF NEW YORK, N. Y., A CORPORATION OF DELAWARE

TYPEWRITING MACHINE

Application filed January 21, 1927. Serial No. 162,420.

This invention relates to typewriting machines, in which webs, usually fan-folded, are typed. These webs are printed with a succession of forms on which the typing is done, and it is customary to employ manifolding material in the form of sheets of carbon interleaved between the plies of the web.

After the plies of one form have been typed, the carbons are stripped therefrom and shifted to the succeeding form, the web being held stationary during such stripping. When in position to be typed upon, the web is looped around the platen, and it is usually impossible to shift the carbons simultaneously while the web is thus looped around the platen, due to the snubbing effect of one carbon upon another, which prevents such shifting. Without having recourse to the usual expedient of displacing the platen to straighten the loop of the web, the snubbing effect may be avoided by stripping the carbons seriatim, beginning with the outermost carbon of the web, which may thus remain looped around the platen.

The trailing ends of the carbons are gripped in the usual blades, which are mounted for stripping purposes on strippers individually movable, and guided at their ends for the usual movement toward and away from the platen.

Among the objects of the invention are to provide means for retracting the carbon-strippers seriatim; to operate such means by an uninterrupted and facile sweep of the hand; to provide a stripper-retracting member which will have a smooth even movement in stripping the carbons and therefore react evenly upon the operator's hand; to provide that the movement of the stripper-retracting member shall proceed without reversal of said movement in recurring carbon-stripping phases, as distinguished, for example, from a stripper-retracting member having a reciprocating movement; and to provide means on each stripper whereby the order and extent of the retraction of the strippers are automatically determined, said last-mentioned means operating to the effect that the rear-most carbon-stripper will be retracted first, then the next one, and the next one, and so on until all the strippers have been retracted.

In conjunction with the last-mentioned means, the provision of a stripper-retracting member operable in recurring carbon-stripping phases makes it possible to retract the maximum number of strippers ever employed, by the same mechanism that is used to retract the minimum number of strippers. In other words, aside from the number of strippers employed, the mechanism for retracting, say eight strippers, would be, as will appear, substantially the same as the mechanism for retracting, say three or four strippers. The uniformity of the stripper-retracting mechanism, irrespective of the number of strippers used, conduces to economy in manufacturing cost because it is not necessary to vary the design of said mechanism according to the number of strippers used. Said mechanism being uniform, there is, aside from an increase in the number of strippers used and a possible extension of the guides of the same, no increase in the weight of said mechanism as the number of strippers used is increased. The advantage of this feature is particularly obvious in the preferred form of the invention where the whole mechanism is to be mounted upon and wholly supported by the typewriter-carriage.

In carrying out the invention, a crank or its equivalent, rotatable by hand, is provided for operating the stripper-retracting mechanism. Before the carbons may be stripped it is necessary to grip and hold the web and cast off the usual feed-rolls, and another object of the invention is to provide means whereby this is done simultaneously and automatically during an initial portion of the crank-movement as the crank is started to operate the stripper-retracting member.

The web-gripping means include a clamp, whereby the leading edge of the web may be clamped in a position gaged by means of the stop usually provided for this purpose. To accommodate different forms, the position of the stop and clamp is shiftable, and the means for automatically operating the clamp are devised so as to be operative for any position of the clamp.

A stripper-retracting member, which shall operate in recurring carbon-retracting

phases, is preferably in the form of an endless belt, which may be geared to the aforesaid operating crank. The belt is run over pulleys that are so spaced and located that 5 one side of the belt runs substantially along the path in which the carbon-stripers move. For retracting the carbon-stripers the belt may have one or more tappets, which, in the crank-operated movement of the belt, will 10 engage said strippers. The carbon-stripers are arranged at the intake side of the platen and normally close to one another. In the process of typing, and as the web is fed around the platen, all the strippers are 15 simultaneously drawn toward the platen to an extent depending upon the length of form typed. In retracting the strippers by means of the aforesaid endless belt and its tappets, the stripper farthest from the platen is to 20 be retracted first, as already mentioned. In the preferred form of means for accomplishing this, there is provided on each carbon-stripper a spring-pressed dog having a portion extending into the path of the endless 25 belt-tappets. The dog may be proportioned and mounted so that it is pushed aside and displaced from the path of the tappets as a tappet encounters it. Beginning with the dog on the stripper nearest the platen all the 30 dogs are thus displaced by the transit of a tappet, until said tappet encounters the dog on the stripper to be retracted, in which case the displacement may be prevented by means 35 of an interponent which has been caused to shift into position to lock said dog.

There is therefore a spring-pressed interponent on each carbon-stripper, and the position of said interponent is controlled by means of the carbon-stripper that, in the 40 order of retraction, is ahead of it, to the effect that when said stripper ahead of it is retracted, said spring-pressed interponent will automatically move into position to prevent the displacement of its corresponding 45 dog. A succeeding transit of the tappet of the endless belt will then be effective by means of the locked dog to retract the last-mentioned stripper. When said last-mentioned stripper is brought up to the previously-retracted stripper, the effective interponent 50 encounters said previously-retracted stripper again and is thereby displaced to the effect that the dog which it has held is released. The dog thus released is displaced 55 as the tappet continues its transit. Each dog is spring-pressed so that it snaps back into normal position following displacement by a tappet. All the interponents on the carbon-stripers are thus controlled except 60 the interponent which is on the rearmost stripper, said rearmost stripper being the one that is always farthest from the platen. In order that the interponent on said farthermost stripper may be withdrawn when said 65 farthermost stripper has been fully retracted,

there may be provided a stationary stop which is encountered by the interponent on the farthestmost stripper, when said stripper reaches the limit of its retraction. In serving to withdraw the interponent, the stationary stop serves the same purpose as a stripper 70 ahead of the farthestmost stripper would serve. Before retraction of the strippers, the interponent of the farthestmost stripper is naturally in effective position because there 75 is no stripper ahead of it.

In the illustrated form of the invention there are shown four carbon-stripers, and the endless belt that retracts said strippers has two tappets thereon. In this case, to 80 retract the four strippers, each tappet must pass along the carbon-stripping range two times. The driving pulley, over which the belt is run, and the gearing from said pulley to the operating crank, are so proportioned 85 that in one revolution of the operating crank a double transit of each tappet is effected. Thus there are four carbon-stripping phases of the belt-movement for each revolution of the crank. Any one of various well-known 90 means may be provided for the purpose of enabling an operator to gage one revolution of the operating crank.

In the gearing connecting the operating crank to the endless belt there is included a 95 shaft, on which the operating crank is mounted, and there may be conveniently fastened to said shaft a single cam which, by suitable connections, is effective to operate the web-gripping means and the means for casting 100 off the feed-rolls. The invention is shown illustratively applied to a typewriter in which the platen is movable for case-shifting purposes, the platen being mounted for this purpose in the usual platen-frame that is shiftable up and down in a main carriage-frame. For the purpose of obtaining rugged construction, the stripper-retracting mechanism, including the operating crank, its shaft, and 105 the aforesaid cam, is mounted on the main 110 frame of the carriage. The web-gripping means and feed-rolls are necessarily mounted on the movable platen-shifting frame. The aforesaid connections whereby said cam may operate the web-gripping means and the 115 means for casting off the feed-rolls may be so devised, as will be shown, as to be operative irrespective of whether the platen-frame is in an upper-case or a lower-case position. 120

A further feature of the invention is the provision of novel means and the arrangement thereof for guiding the carbon-stripers to and from the platen. The difficulty of sufficiently spreading the points of bearing for each stripper, when the strippers are close to one another, is avoided by said novel means and their arrangement. According to said arrangement, as will be shown, there is at each end of the stripper a pair of rolls spread 125

apart sufficiently to prevent tilting and skewing of the stripper as it runs along its guides, and the spread of said rolls is not limited by the closeness of the strippers to one another.

5 This invention is in the nature of improvements upon the devices disclosed in the application of B. C. Stickney, No. 137,229, filed Sept. 23, 1926.

10 Other features and advantages will hereinafter appear.

10 In the accompanying drawings,

Figure 1 is a sectional side elevation, showing the mechanism in which the invention is embodied, said mechanism being applied to the carriage of an Underwood typewriter.

15 Figure 2 is a side elevation, showing the means whereby the platen feed-rolls may automatically be cast off through an initial movement of the operating crank of the mechanism.

20 Figure 3 is a fragmentary view, looking edgewise of one of the strippers, showing details of the displaceable dog on said strippers and how said dog is mounted on the carbon-stripper in relation to the stripper-retracting belt and its tappets.

25 Figure 4 is a perspective view, showing particularly the means for clamping a cross-bar that supports the web-gripping and gag-30 ing means, to the usual table arranged at the delivery side of the platen, said cross-bar being shiftable along said table.

35 Figure 5 is a perspective view, showing the construction of the framework or brackets in which the mechanism of the invention is supported. This figure also shows the manner of attaching said framework or brackets to a main frame of the typewriter-carriage.

40 Figure 6 is a top plan view of the mechanism in which the invention is embodied, and shows particularly the relative positions of the different parts of said mechanism.

45 Figure 7 is a side elevation, showing how the means for automatically controlling the web-clamping device and the feed-rolls may be constructed, so that said control may be effected irrespective of whether the platen is in upper or lower case position.

50 Figure 8 is a view from the rear of the typewriter, and shows some of the carbon-strippers which run on inclined guides. This view shows particularly the manner of operation of the displaceable dogs and the several interponents which control said dogs.

55 Figure 9 is a side elevation, showing how the feed-rolls may be cast off, and the web may be gripped by an initial movement of the operating crank.

60 Figure 10 is a diagrammatic side elevation, showing the relative positions of different parts of the carbon-stripping train at the moment when the stripper farthest from the platen has just been fully retracted.

65 In the typewriting machine to which the

invention is illustratively applied, types 15 strike against the front of a platen 16 mounted on an axle 17 journaled in a platen-frame having ends 18. Said ends are joined to the usual rear paper-shelf 19, which inclines downwardly and forwardly, and curves under and up in front of the platen. The platen-frame is usually shiftable up and down relatively to a main frame 20 of the letter-feeding carriage generally indicated by the number 25. Said carriage travels on the usual guide-rails, of which only the rear one 21 is shown in Figure 1. A multiple-ply web 22 is led from a source of supply over a cross-member 23 which forms part of the mechanism in which the invention is embodied. Said cross-member 23 is so positioned that the web, after passing thereover, is directed toward the platen in an inclined path that conforms to the slope and position of the paper-shelf 19, as shown in Figure 1.

70 The multiple-ply web may include single webs superposed one over the other, or the web may be of the fan-fold type employed with the well-known Underwood method of slitting the folds of the web prior to feeding the web around the platen.

75 Before the web is led around the platen, it is loaded, in the manner well known in the art, by inserting carbon-sheets 24 between the plies of the web. The leading front edges of said carbon-sheets are so positioned that they are somewhat in advance of the first printing line of the first form of the web, which is usually printed with a succession of 80 forms according to which the typing upon the web is done. The leading portion of each form usually has a substantial heading or margin above the first typing line. The rear ends of the carbon-sheets are fastened in the usual manner to carbon-holding blades 27.

85 Said blades are of such length that one end of each blade projects beyond the side edge of the web from between the corresponding plies, and the projecting ends extend alternately from opposite side edges of the web, as shown in Figure 6. The blades are, at these projecting ends, removably attached, by means not shown, to heads 28, which, in turn,

90 are secured to individually-movable carbon-carriers or strippers 29. For guiding the strippers 29 along a path conforming to the direction in which the portion of the web between the cross-member 23 and the platen is extended, there is provided a pair of chan-

95 neled guide-rails 31 along which opposite 100 end-portions of each stripper are guided.

105 A feature of the invention is the novel manner of guiding the end-portions of the strippers along said rails so that the extremities of the bearing of each end-portion along the adjacent rail are separated sufficiently to prevent undue tilting or skewing of the strippers. The end-portions are accordingly 110

115 made to bear upon their respective rails or 120

125 130

other guiding means at two points which are offset both lengthwise and transversely of the strippers. The transverse offset is to effect the desired separation of bearing-points, 5 while the lengthwise offset makes it possible to nest the several pairs of bearing-points so that the usual close grouping of the strippers is possible: The preferred means and the arrangement thereof, whereby this is accomplished, are best shown in Figures 6 and 8. Each end-portion of a stripper has, preferably within the body of the stripper, an up-turned ear 32 upon which is pivoted a bearing-roll 33 that engages an inner channel 30 10 of the adjoining guide-rail 31. Another bearing-roll 34 may be substantially spaced from said roll 33, by having said other roll engage a channel 30^a on the side of the rail opposite to the side engaged by the roll 33, said roll 34 being for this purpose pivoted upon a bent-up extension 35 of the end-portion of the carbon-stripper. Said bent-up extension projects sufficiently forward from the body of the stripper to effect the desired substantial 15 spacing between the rolls 33 and 34. As shown in Figure 6, the up-turned extensions 35 are so formed that the stripper end-portions, notwithstanding said extensions, may be nested one within the other when the carbon-strippers are grouped closely together. Although the guide-rails 31 are preferably channeled as shown in Figures 6 and 8, it is evident that such channeling is not necessary to guide the end-portions of the strippers 20 from opposite sides of said rails. For example, there could be used a pair of rolls on each side of the rail, one running along the top of the rail and one along the bottom of the rail. It is also evident that sliding bearings instead of roller-bearings may be provided. Such sliding bearings, if spread sufficiently apart, as provided for in this feature of the invention, may be just as satisfactory 25 as roller-bearings.

45 To prevent undue displacement of the strippers through the influence of gravity or otherwise there may be provided frictional holding means at each end-portion thereof, said holding means being preferably in the form of a resilient spring 38, which is fastened to the under side of each end-portion. Said spring presses upon the under side of the adjacent guide-rail, as shown in Figure 8, to effect the desired friction to prevent said 30 displacement. To brace the guide-rails they are joined at their upper ends to the cross-member 23 by means of splicing members 39, which may be bent up from said cross-member. Said cross-member, to facilitate 35 the running of the web over it, has the curved form shown in Figure 1. Between the splicing members 39 and the upper ends of the guide-rails 31 there is held a downwardly and rearwardly projecting spur 40, the 40 function of which will presently be described.

In the illustrated embodiment of the invention, the entire carbon-retracting mechanism is supported by the typewriter-carriage 25. To support the mechanism as rigidly as possible, it is principally supported by the frame 20 of said carriage. There are accordingly fastened to said frame a pair of mechanism-supporting brackets which may be designated as a left-hand bracket 41 and a right-hand bracket 42. Figure 5 shows a perspective view of said brackets and the manner of attaching them to the frame 20 of the carriage. To an upstanding portion 43 of the left-hand bracket 41, the lower end of the left guide-rail is fastened. To a similar portion 44 of the right bracket 43 the lower end of the other guide-rail is fastened. 70

In accordance with the purpose of the invention the strippers 29 are retracted by means including a belt 45. To enable 75 said belt to retract the carbon-strippers it is provided with tappets 46, and is so guided that it runs substantially adjacent to and along the path in which the carbon-strippers are guided. To thus guide the belt it is run, as shown in Figure 1, over a lower pulley 37 and an upper pulley 47. Said upper pulley is mounted to freely rotate on a shaft 48 which is fixedly held at its ends in the aforesaid spurs 40 at 80 the upper ends of the stripper guide-rails. The lower pulley 37 is keyed to a rotatable shaft 49, one end of which is journaled in a rearwardly-extending spur 50 of the bracket 41, the other end being journaled in a similar 85 spur 51 of the bracket 42. 90

In the illustrated embodiment of the invention, four carbon-strippers 29 are shown, and for retracting said four strippers the belt 45 is provided with two of the aforesaid 95 tappets 46. As the strippers are to be retracted seriatim, it is evident that each of the two tappets must pass twice along the carbon-stripping range in order that the four 100 strippers may be retracted. The belt is run in the direction indicated by the arrows in Figure 1, and the means whereby said tappets engage the strippers will be presently described. 105

For hand-operation of the belt 45 there is provided a crank 55 which, in accordance with the other features of the invention, is located as best shown in Figure 1. Revolution of said crank serves to run the belt 45 along the carbon-stripping range and it is preferred that one revolution of the crank shall cause the belt 45 to be run to an extent sufficient to effect the seriatim retraction of the number of carbon-strippers provided, which, in this case, is four. To accomplish this, each tappet, as already stated, passes along the carbon-stripping range twice, and the gearing between the belt 45 and said crank is proportioned accordingly. As best shown in Figure 1, said gearing includes, 110 115 120 125

besides the lower pulley 37 and shaft 49, a shaft 56 to which the crank 55 is keyed. For running the belt 45 to the required extent, and in order that the diameter of said pulley 37 shall not be unduly large, it is necessary that said pulley and its shaft 49 make a comparatively large number of turns for each revolution of the crank 55. To avoid awkward proportions of the gearing between the crank-shaft 56 and said shaft 49, an intermediate shaft 58 is provided. Said intermediate shaft 58 is driven by the crank-shaft 56 by means of a belt 59, which is run over a pulley 60 keyed to said intermediate shaft 58 and over a pulley 61 keyed to the crank-shaft 56. The intermediate shaft 58 in turn drives the lower pulley-shaft 49 by means of a gear 63 keyed to said intermediate shaft, said gear meshing with a pinion 64 on said lower pulley-shaft 49.

The intermediate shaft 58 is journaled in the upstanding portion 43 and in an upstanding side 65 of the left bracket 41, and the bearing-holes for said intermediate shaft are indicated in Figure 5 by the number 66. One end of the crank-shaft 56 is also journaled in said side 65, the other end being journaled in an opposite leg 67 of said bracket 41. To prevent the belt 45 from being run reversely, there may be provided a ratchet-and-pawl arrangement, which includes a ratchet-wheel 68 that may be fastened to the belt-driving shaft 49 and may be engaged by a resilient spring 69 that serves as a pawl for checking reverse rotation of said ratchet-wheel, and said belt-driving shaft on which it is mounted. Said spring-pawl may be fastened, as shown in Figures 1 and 6, to a projection 71 extending from the side 65 of the bracket 41. For retaining the shaft 49 lengthwise, the outer side of the pinion 64 at one end of the shaft may bear against the left bracket 41, and a collar 72, fastened to said shaft at its other end, may bear against the right bracket 42 as shown in Figure 6. The crank-shaft 55 may be retained lengthwise by reason of a hub 73 of the crank 55 bearing against the side 65 of the bracket 41 and a hub 74 of the crank-shaft pulley 61 bearing against the opposite surface of said side 65.

A suitable device may be provided to enable an operator to gage one revolution of the crank 55. One form of such device is best shown in Figure 1 and includes a block 76 loosely pivoted upon an arm 77 of the crank 55. The block 76, formed as shown in said Figure 1, is pressed against a stop-pin 78 by a spring 79, which is fastened to the hub 73 of the crank, the block 76 being below said hub. Projecting from the crank-side of the bracket 41 are two projections 80 and 81 which are disposed relatively to the block 76, as shown in Figure 1, and are substantially in the path of said block as it is revolved with the crank. The operation of this revolution-gaging de-

vice is as follows: In the normal position of the crank 55, as shown in Figure 1, the spring 79 presses the block 76 against the stop 78 so that as a revolution of the crank 55 is started a corner 83 of said block is in position to lead it over the projection 81. Near the end of one revolution of the crank, the block 76 is again diverted by riding over the projection 80. As said block 76 is thus diverted, the corner 83 encounters for a moment the projection 81, the operator thereby becoming aware that the crank 55 has made one revolution. Just as the corner 83 of the block encounters said projection 81, the block may also escape from the projection 80 and reassume its normal position, as shown in Figure 1, when one revolution of the crank is completed.

The carbon-stripers 29 advance from a predetermined initial position toward the platen, and, as they thus advance, are grouped close together, as shown in Figure 1. For enabling the tappets 46 on the belt 45 to engage the carbon-stripers and effect their seriatim retraction from any advanced position, means, which will now be described, are provided. In effecting said seriatim retraction, the stripper farthest from the platen is the first to be retracted to its initial position, which may be registered by means of a stop 85, which may be shiftably set along one of the guide-rails 31, as shown in Figure 6. A tappet to engage said farthest stripper must first pass the other strippers, and the means on said strippers, whereby a tappet engages the same, must permit such passage of the tappet. The belt 45 must also be permitted to continue its movement after a tappet thereon has retracted not only said farthest stripper but each of the other strippers. There is provided, accordingly, on each stripper, a dog or interponent 86 which must be shiftably mounted so that it may be pushed aside by a tappet. To this end, the dog is pivotally mounted and has portions 87 extending into the path of the tappets. As shown in Figure 8, each dog is pivoted at such a point that said portions may be pushed aside by the passage of a tappet. In its normal position, each dog is held by means of a spring 88 against a lug 89 projecting from the body-portion of the stripper with which said dog is associated. As shown in Figure 8, the portions 87 of each dog are on opposite sides of the stripper-retracting belt 45. By means of said portions 87, disposed at opposite sides of the belt, the tappets cannot escape said portions which thus serve to always keep the belt in proper relation to the several dogs. When a tappet encounters the dog on a stripper that is to be retracted, said dog must be locked so that the retraction of said stripper may be effected.

For locking the several dogs, there is provided on each stripper an interponent 90, which is pivotally mounted so that it may be

5 moved into position to lock the dog. Each interponent is preferably formed as shown in Figure 8, and has a dog-locking portion 91 which may engage the ends of the dog-portions 87 to lock the dog.

10 Each interponent 90, except the one on the stripper farthest from the platen, is in such position that the associate dog is not locked thereby, and is held in such position by reason of the contiguity of the stripper; that is, in a stripper-retracting direction, ahead of it. In order that such contiguity may cause the interponents to be disengaged from their respective dogs, there is associated with said 15 each interponent a lever 92, by means of which the interponent is either held disengaged from its dog or is permitted to move into engagement therewith. Each lever 92 has an arm 93, by means of which a lug 89 20 of the stripper, which is immediately ahead of it, may position said lever 92 to keep the interponent disengaged from its dog. Each lever 92 is pivotally mounted on the same axis as the interponent with which it is associated, and yieldably connected thereto by 25 means of a spring 94. It may be noticed that the arm 93 might have been an integral part of the interponent 90. It is for the reason that the portion 91 of the interponent may 30 escape quickly and to a sufficient extent from the dog 86 that the lever 92, of which said arm 93 forms a part is yieldably connected to said interponent. The manner in which, by means of said yieldable connection, the interponent thus escapes from the dog will be presently described.

35 In any advanced position of the strippers the dog on the stripper farthest from the platen is locked by its interponent because 40 there is no stripper ahead of it to hold said interponent disengaged from its dog. When a belt-tappet 46 engages said dog on the farthest stripper, the stripper is thereby caused to be retracted until it reaches its initial position as determined by the stop 85. When 45 it reaches said initial position, the dog thereon must be released from said interponent to permit the belt to continue its movement for retracting the other strippers. Such release 50 of the dog on the farthest stripper is effected by the reaction between the interponent of said farthest stripper and said stop 85 as said stripper reaches said initial position. The manner of such reaction will 55 be apparent in Figure 8, which also shows the means by which said reaction is effected. Said means include a lever 95 pivoted on said farthest stripper and having an arm 96 similar to the arms 93 of the levers 92 on the other strippers. By means of a link 97 said lever 60 65 65 is connected to an arm 98 which is yieldably connected to the interponent on said farthest stripper in the same manner as the interponents on the other strippers are connected to their respective levers 92. Said

arm 98 is also of the same form as the interponent-engaging arm 98^a of said levers 92.

70 As shown in Figure 8, a tappet having engaged the dog on the farthest stripper, and the belt 45 having thereby retracted said stripper to its initial position, said dog will have been released from its interponent to permit the continued movement of the belt. Said Figure 8 shows the tappet 46 in its continued movement pushing the released dog, 75 and the belt is thereby enabled to continue its movement. The release of the dog on the farthest stripper from its interponent takes place as the arm 96 of the lever 95 encounters the stop 85 and causes said lever to be turned. As said lever 95 is thus turned, the interponent connected thereto is withdrawn from the dog.

80 The stripper farthest from the platen having been retracted to its initial position, the dog on the stripper next in order of retraction will have been locked by its interponent because there is now no stripper immediately ahead of it to engage the arm 93 on the lever 92 corresponding to said interponent. 85 Therefore, in the next transit of a tappet along the carbon-stripping range, said next stripper will be retracted as soon as the tappet engages the dog thereon. The retraction of said next stripper will continue until the 90 arm 93 of the lever 92 thereon encounters the lug 89 of the stripper that was previously retracted. Such encounter will cause the lever 92 to be turned about its pivot in the same manner that the lever 95 on the previously-retracted stripper was turned by encountering the fixed stop 85, and to the same purpose, namely, to withdraw the interponent from the dog and permit the continued movement 95 of the belt 45. Following this, the other strippers are retracted in the same manner as their respective interponents in turn become effective and as, in the completion of a revolution of the crank, the stripper-retracting belt 45 continues its movement. Each interponent becomes effective as it is drawn into engagement with its dog by means of a spring 99. On each stripper, except the farthest stripper, said spring pulls upon the arm 93 of the lever 92 which moves the interponent. The spring 99 for the stripper farthest from the platen pulls upon an arm 100 which is joined to the lower arm 98 whereby the interponent on said farthest stripper is moved.

100 105 110 115 120 125 130 The arms 93 and 96, which encounter the stripper-lugs 89 and the stop 85 respectively, have cam-shaped edges 101 to engage said lugs and stop. Said cam-shaped edges are so formed that when the strippers reach the limit of their retraction the interponents are withdrawn from their respective dogs far enough to insure the return to normal position of the dogs after they have been pushed aside to permit the passage of the tappets. The

springs 94, yieldably connecting the interponents to the arms 98 and 98^a of their respective actuating levers, are of such strength that each spring yields as its lever is first turned 5 when the stripper nears the end of its carbon-stripping movement. There is thus at first a relative displacement between the arm 98 or 98^a and the related interponents 90, such displacement being limited by a lug 103 formed 10 upon the interponent and which engages a side of the arm 98 or 98^a. As each stripper reaches the end of its retractive movement, the arm 98 or 98^a is further displaced, and, having engaged the lug 103, draws the interponent 15 from engagement with the dog. At the moment the interponent escapes from the dog, it is drawn with a snap movement toward the arm 98 or 98^a again, and thus escapes with a snap movement from the dog. The point on 20 the dog at which the interponent-portion 91 engages said dog, and the point at which said dog is pivoted, are so disposed that a tappet engages said dog at a portion thereof that is substantially closer to its pivot than is the 25 point engaged by said interponent-portion 91. In this manner, the reaction upon said portion 91, due to the retraction of the stripper while said portion is holding the dog, is made substantially less than it would be if the tappet 30 engaged the dog at a point farther from its pivot. The disengagement of the interponent from the dog is thereby substantially facilitated.

The dogs may be formed, as shown in Figure 8, in a U-shape, to include the portions 87 that extend into the path of the tappets which, in order to engage both portions 87, project from opposite sides of the belt 45. The tappets may be formed as shown in Figure 3, 40 and according to said figure each of said tappets is made up of a body-portion 105 which passes through the belt and has a head 106 from which extends a tappet-portion 46^a projecting from one side of the belt. The other 45 end of the body-portion projects from the opposite surface of the belt and has the opposite tappet-portion 46^b beyond a threaded portion upon which is threaded a nut 108 by means of which the whole tappet is fastened 50 to the belt.

Figure 3 also indicates the manner in which the dog may be pivoted upon the stripper in order to limit the length of the dog-portions 87 as measured from the pivot-axis of the dog. 55 To this end, said pivot-axis, as shown in Figure 3, is projected within the belt 45. The dog is therefore pivoted from opposite sides of the belt, and means whereby this is best accomplished include a bracket 109 fastened to 60 the stripper and having a portion 110 spaced far enough from the stripper to afford room for inserting the dog between said portion 110 and the stripper. One of two shouldered pivot-screws 111 is threaded into one side of 65 the dog and bears in said portion 110, and

the other of said screws is threaded into the opposite side of the dog and bears in the stripper 29. Each dog is spring-pressed in its normal position by means of the spring 88 which, as already stated, normally holds the dog against the lug 89 of the stripper, one end of said spring being attached to a projection of the yoke 112 which joins the opposite sides of the dog. The other end of said spring 88 may be attached to a stud 113 which may form part of one of the rivets that secure the bracket 109 to the stripper. In order to set the initial position from which the strippers advance and to which they are retracted, the stop 85 may be shifted and may be secured in any position in which it is set on the stripper guide-rail 31 by clamp-screw 114.

The usual feed-rolls 115 co-operate with the platen 16 to move the web around the platen. Said feed-rolls are disposed, in the usual manner, on opposite sides of a shaft 117 in cradles 118, in which they are supported and which may rock upon said shaft 117 for releasing or casting off said feed-rolls. Said cradles have arms 119 so disposed that they embrace flattened portions of a feed-roll-releasing rod 120 in scissor-like manner, to the end that a slight rotation of said releasing rod 120 will displace the cradles 118 and cause the feed-rolls to be released or cast off from the platen. The feed-rolls are pressed toward and against the platen by springs 122 bearing upon the cradles 118. At one end of said rod 120 connection is made, as shown in Figure 2, to the usual finger-piece 121.

After the typing of a form on the web is finished, and before the carbons may be retracted, said feed-rolls must be released or cast off from the platen to relieve the carbons, which are to be retracted, of their pressure. The leading edge of the web must also be gripped and held so that the web is not retracted with the carbons.

A further feature of the invention is the provision of means whereby the feed-rolls are automatically cast off and the web simultaneously gripped in an initial part of the operating movement of the crank 55 and before the tappets engage the carbon-strippers. 110 At the delivery side of the platen there is the usual table 123 against which the leading edge of the web may be clamped as usual to hold said web during carbon stripping. Said table 123 is supported by the ends 18 of the platen-frame. The web is clamped in the usual predetermined position registered by a gage-surface 126 which, in order to accommodate different forms, is shiftable along said table 123. The means, whereby the web is clamped to said table, must therefore shift 115 with said gage-surface, and are accordingly a part of the structure in which said gage-surface is embodied. For holding the leading ends of the web against the table 123 there are clamping pads 127 which, in order to 120 125 130

clamp or release the web, are mounted on the ends of arms 128 fastened to a rockable shaft 129. Said shaft 129 may be journaled in upstanding ears 130 that project from the end portions of a bar 131 that extends across and is shiftably secured to the table 123. On the forward edge of said bar is formed the gage-surface 126 which, as shown in Figure 6, may be structurally divided into a middle portion and two lateral portions. The middle portion of said gage-surface has a rearwardly-bent extension 132 which carries the usual shiftable gage 133 for positioning the web in proper relation to the form-severing knife 125. Said knife extends lengthwise of the platen and is secured at its ends to the table 123. Figures 4 and 7 show means for securing the bar 131 with the clamping and gaging devices thereon in any adjusted position along the table 123. For thus securing said bar 131 and its attachments, and guiding it along the table 123, clamp-screws 124 pass through said bar and through slots 134 in the table 123. Said slots extend in the direction of adjustment of the bar 131 along the table 123. As shown in Figure 4, said bar has on its under side guide-blocks 135 which fit the slots 134. Each block 135 projects slightly below the under surface of the table, and over the part of the block projecting below said surface there fits the channel 137 of a clamping block 138 in which the clamp-screw 124 is threaded. By means of the engagement of the channel 137 with the block 135, turning of the clamping block, when said clamp-screw is loosened, is prevented.

A further feature of the invention is the provision of means whereby the feed-rolls are automatically cast off and the web is simultaneously gripped during an initial part of the operating movement of the crank 55 and before any tappet 46 engages a stripper to retract it. By said last-mentioned means, the feed-rolls are also automatically restored and the web is automatically released at the end of the operating movement of said crank 55 after the strippers have been retracted. Said means whereby the web-clamping device and the feed-rolls are automatically actuated before and after carbon-stripping will now be described. The clamping rock-shaft 129 may be actuated by means of an arm 140, which, as shown in Figure 6, is at the left end of said shaft. In order that said shaft 129 may be rocked to actuate the clamp-pads 127, irrespective of the position of said pads along the table 123, the arm 140 coacts with a member 141 having an element which, in moving said arm, is nevertheless always parallel to the table 123. Said element of the member 141 is preferably in the form of a slot 142 parallel to the table 123 and co-extensive with the range within which the clamping device is shifted. A pin 136 in the end of the arm

140 of the clamping rock-shaft engages said slot 142. For moving the member 141 in parallelism with the table 123, it is pivotally connected, as shown in Figures 1 and 9, at its upper end to an arm of a bell-crank 144, and at its lower end to a similar arm of a bell-crank 145, the other arms of said bell-cranks being connected by a link 146. Said bell-cranks are pivotally mounted upon ears 147 projecting from the paper-table 123. The bell-cranks, the clamp-actuating arm 140, and the arms 128 upon which the clamp-pads 127 are mounted, are so disposed that the clamp-pads are disengaged from the table 123 when the upper bell-crank 144 is against a stop 148 that projects from the ear 147 upon which said bell-crank is pivoted.

Means, whereby the operating movement of the crank 55 may control the feed-rolls 115 and the web-clamping device before and after the strippers are retracted, are particularly shown in Figures 1 and 9. A cam 149 is keyed to the crank-shaft 56 and has a camming notch 150. In the normal position of said crank 55, a roll 151 of a follower-arm 152 for said cam rests in said notch 150. Said follower-arm 152 is part of a lever 153 which may be pivoted upon an ear 154 extending from the paper-table 123. A spring 155 (Figure 1) draws said follower-arm 152 toward the cam 149. In order that the cam-controlled movement of said lever 153 may control the clamping device and the platen feed-rolls, a lower arm 157 of said lever is connected to the link 146 of the clamping device and to the feed-roll-releasing rod 120. Connection between said lower arm 157 and said link 146 is made by means of a spring 159. As shown in Figure 1, the pull of said spring 159 holds the link 146 endwise, so that a stop-pin 160 projecting from the side of said link normally bears against a side of said arm 157 of the cam-controlled lever 153. The throw of said cam-lever 153 is such that there is an excess of movement of the arm 157 as far as web-clamping purposes are concerned. In this excess of movement the spring 159 is stretched as the clamping pads 127 press the web against the table 123, as shown in Figure 9. It is evident that there is thus a resilient clamping pressure upon the web by the clamping pads 127. Owing to this resilient clamping pressure, the clamping pads accommodate themselves to different thicknesses of the web, and proper functioning thereof is not dependent upon an exact throw of the cam-controlled lever 153. One end of said spring 159 is attached to a projection 162 of the link 146, the other end of the spring being attached to the arm 157 of the cam-controlled lever 153. Said arm 157 is also connected to an arm 163 at the end of the feed-roll-releasing rod 120. The end of said rod, to which said latter arm 163 is connected, is opposite the end of the rod to 130

which the aforementioned finger-piece 121 is connected. For connecting said arm 163 and the arm 157 of the cam-lever 153 there is a link 164 pivotally connected at its lower end to the arm 163. The upper end of said link 164 has a slot 165 engaged by a stud 166 in the end of the arm 157. The purpose of the pin-and-slot connection thus formed is that the feed-roll-releasing rod may be controlled by the finger-piece 121 independently of the cam-controlled lever 153.

Figure 9 shows how, by the means just described, the feed-rolls are automatically cast off and the web is automatically gripped during an initial portion of the operating movement of the crank 55. As the crank continues its revolution the roll 151 of the cam-controlled lever 153 rides on the dwell 168 of the cam 149. At the end of the revolution of the crank, the notch 150 of said cam is in its normal position again, causing the cam-controlled lever 153 to be rotated as the roll 151 thereof, under the influence of the lever-spring 155, drops into said notch. As the lever 153 thus rotates, the feed-rolls are restored to the platen and the clamping pads 127 are caused to be withdrawn from the web. In order that the feed-roll springs 122 may aid in the restoration of said feed-rolls, it is desirable that the feed-roll-releasing rod be not rotated to such an extent that the wide part of its flattened portions are on a dead center with the cradle-arms 119 that embrace said portions. A rotation of the rod 120 to the extent indicated in Figure 9 is usually sufficient to cast off the feed-rolls enough to relieve the carbons of their pressure.

The cam 149 for automatically releasing the feed-rolls and clamping the web may be said to be supported by the carriage-frame 20, while the web-clamping means and the feed-rolls are supported in the platen-frame that is shiftable up and down relatively to said carriage-frame, said shifting of the platen-frame being for the purpose of positioning the platen for either upper-case or lower-case typing, the platen being normally in lower-case position. It is assumed that the platen is in said lower-case position when the strippers are to be retracted. There may be occasions, however, where the platen is, by the usual means, not shown, fixedly set in its upper-case position so that all the characters typed are upper-case characters. Where it is desired to retract the carbon-strippers while the platen is in upper-case position, a modification of the means connecting the cam 149 to the web-clamping means and feed-roll-releasing means is necessary. There is accordingly shown, in Figure 7, means whereby said cam may actuate the clamping device and release the feed-rolls irrespective of whether the platen is in upper-case or lower-case position. The hereinbefore-described cam-controlled lever

153 may, according to said Figure 7, be regarded as divided into two portions, one a portion 175 pivoted at 176 to the carriage-frame 20, and the other a portion 177 pivoted to the ear 154 projecting from the table 123. The latter portion 177 has a pin 178 engaged by an edge 179 of the portion 175, said edge extending in the direction in which the platen is shifted. The arm or portion 175 carries a cam-follower roll 151^a. It will be noted that the effective length of the portion 175, from the point 176 at which it is pivoted, should be made as large as possible so that the difference in the movements of the portion 177 may be negligible, said difference resulting from the shifting of the platen-frame which supports said portion 177. The platen-frame, it will be understood, is shifted up and down by means including the usual shift-rod 181 having at each end an arm 182 that engages the sides 18 of the platen-frame.

In the normal position of the operating crank 55, the tappets 46 on the stripper-retracting belt 45 should be in a position that is clear of the range of normal movement of the carbon-strippers toward the platen. Such a position is indicated in Figure 1. The pulleys 37 and 47, over which said belt 45 is run, have clearance-pockets 169 to clear the tappet-portions 46^a projecting from the inner side of said belt. In order that the belt 45 may be positively driven by the crank 55, and also in order that the tappets 46 may move in proper synchronism with said crank, there may be formed in said belt forty-five holes 170 engaged by sprocket-teeth 171 formed in the pulleys 37 and 47 over which said belt is run. To this end, the belt 59 is also provided with holes 172 which engage sprocket-teeth 173 formed in the pulleys over which said belt 59 is run.

The usual adjustable web-guides 180 may be disposed upon the shaft 48 that is at the upper ends of the guide-rails 31.

Variations may be resorted to within the scope of the invention, and portions of the improvements may be used without others.

Having thus described my invention, I claim:

1. In a multiple-ply web-manifolding typewriting machine, the combination with a platen-carriage having a carbon-stripper movable toward and from said platen upon guides carried by the carriage, of a belt having means on the carriage for guiding and running said belt parallel to the path of said stripper, means carried by said belt, operative to retract said stripper, a stop, and means movable with said stripper co-operating with said stop, whereby the extent of retraction of the stripper is automatically limited by said stop regardless of a continued movement of the belt or the extent of said continued movement.

2. In a multiple-ply web-manifolding typewriting machine, the combination with a platen, a carbon-stripper movable toward and from said platen, and guiding means for said stripper, of an endless belt, means for guiding and running said belt parallel to the path of said stripper, means carried by said belt and operative during the run of the belt to retract said stripper, a stop, and means carried by said stripper and cooperating with said stop, whereby the extent of retraction of the stripper is automatically limited by said stop regardless of a continued movement of the belt or the extent 15 of said continued movement.

3. In a multiple-ply web-manifolding typewriting machine, the combination with a platen-carriage having a multiplicity of carbon-strippers individual to superposed 20 carbons and individually retractable from said platen, and guiding means on the carriage for said strippers of an endless belt, means for running said belt adjacent the path of said strippers, and means carried by 25 said belt and operative as it is run along said path, to automatically retract said strippers one at a time beginning with the outermost carbon-sheet.

4. In a multiple-ply web-manifolding typewriting machine, the combination with a platen-carriage having a multiplicity of carbon-strippers individual to superposed carbons and individually retractable from 30 said platen, and guiding means on the carriage for said strippers, of an endless belt, means for driving in a carbon-stripping direction said belt adjacent the path of said strippers, and means whereby said belt becomes operative as it is run along said path, 35 to pass certain of said strippers and actuate only the stripper farthest from the platen.

5. In a multiple-ply web-manifolding typewriting machine, the combination with a platen-carriage having a multiplicity of carbon-strippers individual to superposed carbons and individually retractable from 40 said platen, and guiding means on the carriage for said strippers, of an endless belt, manual means for driving said belt in a carbon-stripping direction adjacent the path of said strippers, interponents carried by each stripper, and means carried by said belt and cooperative with said interponents, as the belt 45 is run along said path, to selectively retract said strippers one at a time beginning with the outermost carbon-sheet.

6. In a multiple-ply web-manifolding typewriting machine, the combination with a platen-carriage having a multiplicity of carbon-strippers individual to superposed carbons and individually retractable from 50 said platen, and guiding means on the carriage for said strippers, of an endless belt, means operated by a revolute handle for driving 55 said belt adjacent the path of said strippers,

means carried by said belt operable to retract said strippers one at a time beginning with the outermost carbon-sheet, the means operated by the handle being operable by one revolution of the handle to drive the belt sufficiently to retract all the strippers, and stop-means to enable an operator to gage one revolution of said handle. 70

7. In a multiple-ply web-manifolding typewriting machine, the combination with a platen-carriage having a multiplicity of carbon-strippers individual to superposed carbons and individually retractable from 75 said platen, and guiding means on the carriage for said strippers, of an endless belt, means for running said belt reversely to the platen-fed direction of said strippers, said belt being normally stationary, and means carried by said belt operable, when said belt is run along its path, to retract said strippers one at a time, 80 said last-mentioned means being so spaced upon said belt that they are not in the path of said strippers when said belt is in its normal stationary position. 85

8. In a multiple-ply web-manifolding typewriting machine, the combination with a platen-carriage having a multiplicity of carbon-strippers individual to superposed carbons and individually retractable from 90 said platen, and guiding means on the carriage for said strippers, of an endless belt, means for driving said belt in a carbon-stripping direction parallel to the path of said strippers, tappets on said belt, and means carried by each stripper and coacting with said tappets during the travel of the belt, whereby said strippers become operative one at a time beginning with the outermost carbon-sheet. 95

9. In a multiple-ply web-manifolding typewriting machine, the combination with a platen-carriage having a multiplicity of carbon-strippers individual to superposed carbons and individually retractable from 100 said platen, and guiding means on the carriage for said strippers, of a belt, means for driving said belt in a carbon-stripping direction parallel to the path of said strippers, tappets on said belt, means carried by each stripper coacting with said tappets during the travel of said belt that become operative upon said strippers one at a time to strip a carbon, and a stop on the carriage, whereby the extent of retraction is automatically limited. 105

10. In a multiple-ply web-manifolding typewriting machine, the combination with a platen-carriage having a multiplicity of carbon-strippers individual to superposed carbons and individually retractable from 110 said platen, and guiding means on the carriage for said strippers, of a belt, means for running said belt parallel to the path of said strippers, tappets on said belt, means on said strippers coacting with said tappets during the travel of said belt that become operative upon said strippers one at a time to strip a carbon, and 115 120 125 130

stopping means, whereby the extent of retraction of said strippers is automatically limited, said stopping means including a stationary stop upon the carriage coacting with the 5 stripper that is retracted first and also including a stop on all the other strippers except the one that is retracted last.

11. In a multiple-ply web-manifolding typewriting machine, the combination with a 10 platen-carriage having a multiplicity of carbon-strippers individual to superposed carbons and individually retractable from said platen, and guiding means on the carriage for said strippers, said strippers normally 15 grouped next to one another along said guiding means and movable in a group toward said platen from a predetermined initial position, of a belt having tappets thereon, means for running said belt parallel to the path of 20 said strippers, a spring-pressed dog displaceably mounted upon each stripper to extend into the path of said tappets to be displaced by said tappets to permit their free passage, and a shiftable spring-pressed interponent 25 mounted upon each stripper, and operable in a normal position thereof to lock the associated dog thereon and a stop on the carriage operative to determine the disposition of the 30 interponent relatively to the dog on the stripper farthest from the platen.

12. In a multiple-ply web-manifolding typewriting machine, the combination with a 35 platen-carriage having a multiplicity of carbon-strippers individual to superposed carbons and individually retractable from said platen, and guiding means on the carriage for said strippers, said strippers normally grouped next to one another along said guiding means and feedable as a group toward 40 said platen, of a traveling belt having tappets thereon, means for running said belt parallel to the path of said strippers, a spring-pressed dog displaceably mounted upon each stripper to extend into the path of said tappets to be 45 displaced by said tappets to permit their free passage, a shiftable spring-pressed interponent mounted upon each stripper and operable in a normal position to lock the associated dog thereon, stop-means on the carriage 50 operative to determine the disposition of the interponent relatively to its dog on the stripper farthest from the platen, and means whereby the disposition of the interponent on each of the following strippers is controlled 55 by means mounted upon the preceding stripper.

13. In a multiple-ply web-manifolding typewriting machine, the combination with a 60 platen-carriage having a multiplicity of carbon-strippers individual to superposed carbons and individually retractable from said platen, and guiding means on the carriage for said strippers, said strippers normally 65 grouped next to one another along said guiding means and feedable as a group toward

said platen, of a traveling belt having stripper-engaging tappets thereon, means for running said belt parallel to the path of said strippers, a dog on each stripper extending into the path of said tappets and pivotally 70 mounted to be displaced by said traveling tappets for a free passage thereof, an interponent on each stripper co-operative with the dog thereon, said interponent being normally operative to lock the dog and thereby prevent 75 its displacement and drive its stripper, and means on each stripper operative, in a stripper-retracting direction, to vibrate the interponent of an advancing stripper, release its locked-up dog, and separate the stripper from 80 the control of the driving tappet.

14. In a multiple-ply web-manifolding typewriting machine, the combination with a platen-carriage having a multiplicity of carbon-strippers individual to superposed carbons and individually retractable from said platen, and guiding means on the carriage for said strippers, said strippers normally grouped next to one another along said 85 guiding means and feedable as a group toward said platen, of a traveling belt having stripper-engaging tappets thereon, means for running said belt parallel to the path of said strippers, a dog on each stripper extending into the path of said tappets and pivotally 90 mounted to be displaced by said traveling tappets to permit the free passage of said tappets, an interponent on each stripper associated with the dog thereon, said interponent being normally operative to lock the dog and thereby prevent 95 its displacement and drive its stripper, means on each stripper operative, in a stripper-retracting direction, to vibrate the interponent of an advancing stripper to release its dog, and a stop on the carriage operative to establish a normal stripper position for the first stripper restored, whereby each successive dog may be released seriatim from 100 its driving tappet for a predetermined carbon-stripping movement.

15. In a multiple-ply web-manifolding typewriting machine, the combination with a platen-carriage having a multiplicity of carbon-strippers individual to superposed carbons and individually retractable from said platen, and guiding means on the carriage for said strippers, said strippers normally grouped next to one another along said 115 guiding means and feedable in a group toward said platen, of a traveling belt having tappets thereon, means for driving said belt parallel to the path of said strippers, a dog pivotally mounted on each stripper and formed with parallel arms that straddle the 120 belt and extend into the path of said tappets, said tappets being assembled to the belt to project from both faces of the belt to jointly engage and displace each dog, and means 125 carried by each stripper operative to prevent 130

the displacement of the dogs and effect a carbon-stripping movement.

16. In a multiple-ply web-manifolding typewriting machine, the combination with a platen carriage having a multiplicity of carbon-stripers individual to superposed carbons and individually retractable from said platen, guiding means on the carriage for said strippers, said strippers normally grouped next to one another along said guiding means and feedable as a group toward said platen from predetermined initial positions and a stop adjustable along said guiding means for registering said initial positions, of a belt having tappets thereon, means for driving said belt parallel to the path of said strippers, and means on said strippers rendered operative as the belt is driven along said path, to retract said strippers seriatim to said initial positions.

17. In a multiple-ply web-manifolding typewriting machine, the combination with a platen-carriage having a multiplicity of carbon-stripers individual to superposed carbons and individually retractable from said platen, and a pair of guide-rails on the carriage for said strippers, of a travelling endless belt, a pair of pulleys over which said belt is run, supporting means for said pulleys operative to guide the belt parallel to said rails and adjacent the path of said strippers, operating means connected to one of said pulleys for driving the belt, and means rendered operative by the driven belt which renders the strippers operative to retract the carbons seriatim.

18. In a multiple-ply web-manifolding typewriting machine, the combination with a platen, a platen-carriage having a multiplicity of carbon-stripers individual to superposed carbons and individually retractable from said platen, and a pair of guide-rails on the carriage for said strippers, of a traveling endless belt, a pair of pulleys supported by one of said guide-rails, over which said belt is driven to run parallel to said rail and parallel to the path of said strippers, one-way operating means also supported by said carriage and connected to one of said pulleys to drive the belt, and means rendered operative by the driven belt, which renders the strippers operative to be retracted one by one.

19. In a multiple-ply web-manifolding typewriting machine, the combination with a platen-carriage having carbon-stripping means feedable toward and retractable from said platen, a crank, and means operable by said crank to engage and retract said carbon-stripping means, of a clamping device for holding the web during the stripping of the carbon, and connections driven by the crank and operative upon the clamping device to automatically grip the free ends of the web before the carbon-stripping means become operative, and, after the ensuing retraction

of the carbon-stripping means, the web-clamping device is automatically released.

20. In a multiple-ply web-manifolding typewriting machine, the combination with a platen-carriage having feed-rolls co-operating with said platen for feeding a web in typing, carbon-stripping means feedable with the web toward said platen, and a crank operably connected to engage and retract said carbon-stripping means, of a web-clamping device, means driven by said crank and operatively connected to said clamping device to clamp the web before the carbon-stripping means are effective, and operative after the ensuing retraction of the carbon-stripping means to automatically release the clamped web, and means connected to said crank-driven means operative to automatically cast off the web-feeding rolls before the carbon-stripping means are effective, and subsequently restore the feed-rolls after the retraction of the carbon-stripping means.

21. In a multiple-ply web-manifolding typewriting machine, the combination with a platen-carriage having a plurality of carbon-stripers individual to superposed carbon-inlays and individually retractable from a platen-fed position of the web, and guiding means on the carriage to determine a path for said carbon-stripers, of a stripper-retracting member movable parallel to the path of the strippers and carrying stripper-driving means at recurring intervals, and mechanism carried by said strippers and co-operative with said driving means to retract the carbon-stripers seriatim beginning with the outermost carbon-sheet.

22. In a multiple-ply web-manifolding typewriting machine, the combination with a non-displaceable platen and a carbon-carrier feedable towards said platen between work-sheets fed around said platen in typing, of an endless belt movable reversely to the platen-fed direction of the carbon-carrier, said belt provided with means operative automatically during the transit of said belt to pick up and automatically release said carrier for a carbon-stripping motion of predetermined extent.

23. In a typewriting machine, the combination with means for feeding superposed work-webs around a non-displaceable platen, and a reciprocable carrier for a carbon-sheet interleaved between the work-webs and feedable with the webs around the platen in typing, of manually operable means on the carriage traveling parallel to the path of the carbon-carrier in a carbon-stripping direction and operative during a continuous movement of said manually operable means to pick up the carrier, strip the carbon from a typed area of the webs, and then release the carrier at a normal position.
